UNITED STATES PATENT OFFICE.

EUGENE C. YEOMAN, OF DE KALB, ILLINOIS.

SEAL DEVICE.

No. 926,161.

Specification of Letters Patent.

Patented June 29, 1909.

Application filed August 29, 1908. Serial No. 450,897.

To all whom it may concern:

Be it known that I, EUGENE C. YEOMAN, a citizen of the United States, residing at De Kalb, in the county of Dekalb and State of Illinois, have invented certain new and useful Improvements in Sealing Devices, of which the following is a specification, reference being had to the accompanying drawing.

10 This invention relates to improvements in sealing devices adapted to be used for sealing cars, express trunks or other articles, so as to prevent any unauthorized opening of such articles without rupturing the seal.

15 The object of my invention is to provide a cheap, simple and secure device of this character, and I accomplish this object by the construction shown in the accompanying drawing and hereinafter particularly 20 described.

That which I believe to be new will be set forth in the claim.

In the drawing,—Figure 1 is a perspective view of my improved seal, in locked position, the casing portion being partly broken away. Figs. 2 and 3 are details, considerably enlarged, of the end portions of my improved sealing strip. Fig. 4 is a longitudinal vertical section through the 30 sealing strip and the projecting casing, the section being taken at line 4—4 of Fig. 5, and Fig. 5 is a cross section at line 5—5 of Fig. 4.

Referring to the several figures of the drawing in which corresponding parts are indicated by the same reference numerals— 35 6 indicates a strip of thin sheet-metal provided with a series of pairs of slits 7 and 8 cut at right angles to the side edges of the strip whereby is left between each pair a small plate 9 of approximately rectangular shape, each of said plates being depressed so that its outer face lies slightly below the inner face of the body portion of the strip 40 6, the depression of the plates 9 being preferably accomplished by the same operation of the tool or die that cuts the slits 7 and 8. One of these pairs of slits and intermediate plate portions is formed a short distance from one end of the metal strip, and as many more may be provided at suitable intervals as desired. At a little distance 45 from the opposite end of the strip, the strip is cut to produce two short tongues, 10 and 11 respectively, the tongue 10 being the

nearer to the end of the strip. Both tongues are cut so as to have their attached ends toward the adjacent end of the strip, as clearly shown in Fig. 3, but the tongue 11 is turned back over the outer face of the strip so 60 that its free end can be brought adjacent to the free end of the tongue 10. The tongue 10 is raised above the outer surface of the strip 6 and will lie over and slightly project beyond the free end of the tongue 11, 65 as clearly shown in Fig. 3. 12 is a small projection stamped in the strip 6 in position to be under the turned-back tongue 11 so as to insure such tongue being at all times held above the surface of the strip. 70

13 indicates a casing inclosing that portion of the strip 6 in which the two tongues 10 and 11 are formed and of a length to project at each end some little distance past the tongues, as clearly shown in Fig. 4. The 75 casing is preferably formed of a single piece of metal of the required width folded upon itself, as shown, so as to leave its ends open. When in place on the strip over said tongues it is to be secured against movement, and 80 in the construction shown it is secured by bending back the strip 6 as shown at 14 so that the turned end portion will lie against the lower face of the casing and then giving to this portion of the strip near its extreme end another bend as shown at 15, thereby forming a hook portion 16 which is inserted in the casing and lies beneath the inner face of the strip 6. 85

With the strip formed as described and 90 the casing secured over the tongues 10 and 11, the device will be used for sealing purposes as follows; the strip will be passed through staples or eyes on the two parts that are to be secured together, as for example, 95 a car-door and the car-body, and that end of the strip in which are formed the cross-slits 7 and 8 and depressed plate portions 9 will be inserted into that end of the casing 100 that is adjacent to the bend 14. The strip may be pushed into the casing to any desired extent as each depressed plate portion will of course ride over the tongue 10 whose free end is extended in the direction in which 105 the strip is being moved and it cannot be caught by the end of the reversely-turned tongue 11 as such end is beneath and protected by the end of the tongue 10, as clearly shown in the enlarged detail in Fig. 3. When, 110 however, the strip has been inserted as far

as desired, a short backward pull on the strip will cause the tongue 10 to enter one of the slits 8 which it is enabled to do by reason of the depressed plate portion 9 adjacent to such 5 slit, such depressed portion then coming of course beneath said tongue 10. This backward pull to cause said engagement of the tongue 10 with the strip is continued sufficiently to bring the other slit 7 in position 10 to allow the end of the turned tongue 11 to enter it, said tongue 11 springing up as the forward edge of the depressed plate portion is drawn beyond the end of said tongue. A slight forward push on the strip then 15 causes the tongue to project through said slit 7 and lie over the plate, as clearly shown in Fig. 4. With both of the tongues thus engaging the strip it cannot be disengaged from the casing, and consequently the door 20 or other movable part which the strip en-

gages cannot be opened without destroying the strip.

What I claim as new and desire to secure by Letters Patent is,—

The combination with an open ended casing, of a sealing strip secured thereto, said strip being provided at that portion enclosed by the casing with two oppositely-directed tongues both raised above the same face of the strip, and said strip being also 25 provided on that portion that is adapted to be moved into the casing with two slits extending crosswise of the strip, that portion of the strip between said slots being depressed.

EUGENE C. YEOMAN.
